UNITED STATES PATENT OFFICE.

WILLARD W. STEARNS, OF HOLYOKE, MASSACHUSETTS.

WEFT BINDING AND CUTTING DEVICE FOR LOOMS.

1,219,182.

Specification of Letters Patent. Patented Mar. 13, 1917.

Application filed September 21, 1915. Serial No. 51,888.

To all whom it may concern:

Be it known that I, WILLARD W. STEARNS, a citizen of the United States of America, and resident of Holyoke, in the county of 5 Hampden and State of Massachusetts, have invented certain new and useful Improvements in Weft Binding and Cutting Devices for Looms, of which the following is a full, clear, and exact description.

10 This invention relates to devices employed in automatic looms of a well known type in which bobbins from the magazine are periodically delivered into the shuttle while the latter is boxed, causing the expulsion 15 from the shuttle of the bobbin from which the weft thread or filling has become exhausted.

In automatic looms of the type referred to, the means for replenishing the bobbins 20 in the shuttle and causing the expulsion of the exhausted bobbins is controlled by a so-called "feeler" motion or mechanism operating in conjunction with which is a device opposite the location of the inner end of the 25 shuttle box which is operable to both temporarily bind the weft or filling and to sever it near where it is bound, and also operative thereafter to release the bound and severed portion of the weft so that the 30 remnants of the weft from an exhausting bobbin may not become entangled with that of the freshly supplied bobbin or become woven into the cloth.

The features of improvement in the combined feeler thread binder and cutter of 35 the general kinds or constructions now commercially employed in automatic looms reside—in a non-metallic movable clamp member, most advantageously composed of fiber 40 board, fiberoid, or like hard composition or material which in its coaction with the relatively stationary adjacent member is operative for its many times repeated binding actions without having a groove worn 45 by the thread from its working edge across the binding face thereof whereby the thread after a while is allowed to slip and be pulled out; and in the formation of a hollowed out or reduced portion of the fiberoid or 50 non-metallic movable binder member of the device at the central portion thereof for insuring that the same will not become warped, bent or twisted, but will lie face- 55 wise flush and flat against the metallic member with which it coacts.

The invention is described in conjunction with the accompanying drawings and is set forth in the claims.

In the drawings:

Figure 1 is a side elevation showing the 60 combined feeler thread binder and clamp with the jaw members thereof half way between open and closed positions.

Fig. 2 is a horizontal sectional view on line 2—2, Fig. 1. 65

Fig. 3 is a cross sectional view on line 3—3, Fig. 1, as seen in the direction of the arrow.

Fig. 4 is a sectional view similar to Fig. 3, but showing fully closed relations of the 70 relatively movable parts.

Fig. 5 is a face view of the movable cutting blade comprised in the device as seen oppositely faced from the representation 75 shown in Figs. 1 and 2.

In the drawings, A represents the carrier and support of the combined thread binder and cutter for a loom; B represents a steel blade or plate mounted on the face of the carrier support and constituting the 80 fixed jaw of the thread cutter. C is a metallic plate facewise parallel with and spaced from the carrier support and the fixed jaw B, and so connected or engaged therewith as to be substantially immovable relatively 85 thereto.

D and E represent combined and face- 90 wise adjacent cutter and binder jaws together pivotally mounted on the pivot a which is supported by the carrier support and extends through the spaced binder jaw C, and which are interengaged by a pin and dowel indicated at b so that one may not have any swinging movement relatively 95 to the other.

The cutter jaw D has a projecting arm d through means of which the movable parts of the binder and cutter are actuated in the operation of the loom.

The parts C, E and B are held in their 100 proper relations and have frictional face- wise binds one with another by means of the headed stud f and the flat metal spring g.

The device, comprising coacting shear knives or cutter jaws, and coacting binder 105 jaws or members, is in the general aspect seen in Fig. 1, very much as now appearing in the bobbin feeler motion of a loom of the Northrop type, and as represented in Letters Patent of the United States to 110

Northrop, Sept. 17, 1907, No. 866,052, and to Rhoades December 17, 1912, No. 1,047,448, the device, however, comprising the structural features hereinbefore referred to and 5 which will be now particularly pointed out:

The pivotally mounted and movable binder jaw E is of a suitable non-metallic material such as the well known commercial hard fiber or fiber board and by the 10 use of which the liability of the thread or yarn becoming cut when it should only be bound and temporarily held is obviated.

This binder jaw member E of fiberoid or equivalent material has the opposite sides 15 between the end portions thereof reduced in thickness as indicated at *h h* in Fig. 2, so that there will be facewise bearings of the end portions only of the binder member against the portions of the device at 20 opposite sides thereof, whereby warping of the binder jaw member is prevented.

I am aware than non-metallic clamping jaws or members in the binding portion of a thread binder and cutter have been here- 25 tofore proposed and used only to a limited extent and with unsatisfactory results. In these cases the non-metallic member of the binder has been comprised in the fixed, and not the movable member.

30 It has been proved by practical use that all fixed non-metallic members of the binder are inefficient in the carrying out of the desired purpose as the thread has been drawn down and across the face of 35 the non-metallic member by the action of the swinging jaw when clamping the thread, causing a groove to wear in the relatively immovable non-metallic member and allowing the thread to easily pull 40 or slip out.

By the use of this movable, non-metallic binding jaw the thread is carried down as one with the jaw in the closing of the latter,—there is no drawing motion of the 45 thread on and across the jaw and the wearing of the jaw by the thread is inappre- ciable.

This has been proven by the use of a device in which the movable binding member 50 was composed of fiberoid in a loom constantly running for over eight months and in which the shuttle bobbin was transferred on an average of every three minutes, and calling at each of such frequent times for 55 the operation of the binder and cutter, and after all of which period and operations the binder was not measurably impaired.

The blade or knife D of the swinging jaw of the thread cutter or shear has a 60 groove *i* adjacent its cutting edge and within its side which is next to the blade B with which such groove provided jaw coats.

As will be perceived in Fig. 4, which indicates the cutter jaw D in closed relation

to the jaw B, there is but slight facewise 65 area of the adjoined sides of these jaws which lie one against or close to the other,—the groove leaving a free or clearance space so that the fine hair-like fibers which may be thrown outwardly from the 70 yarn may not be clamped and bound in the knife to result in the holding of the thread at the time the bobbin is being expelled from the shuttle.

The outer jaw C which is parallel with 75 and spaced from the carrier support D has at its end, outwardly divergent thread-guiding horns *j* and *m*, the lower one of which is in the plane of the swinging movement of the fiberoid binding member E, 80 while the upper horn *j* is transversely outwardly inclined as indicated in Fig. 3 for creating a free space between it and the binder blade E, whereby the thread which had been bound between the lower horn and 85 the binder blade, on the opening or releasing movement of such blade, will not improperly again be bound between the blade and the said upper, inclined, horn.

I claim:—

1. In a device of the character described, a supporting and carrying member having a normally fixed cutter jaw and a binder jaw plate opposite and separated from the supporting member, and non- 90 movable relatively thereto, a combined pivotally mounted cutter jaw and a non-metallic binder jaw between the fixed cutter jaw and the binder jaw plate, which latter in its swinging movement facewise 100 on the side of the outer binder jaw is operative when such jaws are closed to carry the thread to a position between, and to be bound by, the coacting movable non-metallic binder jaw member and the adjacent 105 relatively immovable binder jaw member.

2. In a device of the character described, a supporting and carrying member having a metallic binder jaw opposite and separated therefrom and a pivoted binder jaw 110 facewise in relation to said jaw composed of a non-metallic material and having intermediate portions of the sides thereof reduced to permit facewise bearings of the end portions of such member against the 115 portions of the device at opposite sides thereof for preventing warping of the said non-metallic jaw member.

3. In a device of the character described, a supporting and carrying member made 120 with a cutter jaw thereon, and having a metallic jaw opposite and spaced from such cutter jaw, a metallic cutter blade or plate, and a plate forming a binder member, which binder member and said cutter plate 125 are facewise adjoined and engaged one with the other, and together pivotally mounted for swinging movements on the

supporting and carrying member, between same and the said opposite spaced jaw, and said pivoted member being composed of a non-metallic material such as fiberoid and having intermediate portions of the sides thereof reduced to permit facewise bearings of opposite sides of the end portions of such member against the cutter

blade and the said spaced jaw for the purpose explained.

Signed by me at Springfield, Mass., in presence of two subscribing witnesses.

WILLARD W. STEARNS.
